UNITED STATES PATENT OFFICE.

HAROLD CARLE, OF BUFFALO, NEW YORK, ASSIGNOR, BY MESNE ASSIGNMENTS, TO VORTEX MFG. CO., OF CHICAGO, ILLINOIS, A CORPORATION OF ILLINOIS.

CUP DISPENSER.

Application filed January 12, 1924. Serial No. 685,784.

To all whom it may concern:

Be it known that I, HAROLD CARLE, a subject of the Kingdom of Great Britain, residing at Buffalo, in the county of Erie and 5 State of New York, have invented certain new and useful Improvements in Cup Dispensers, of which the following is a full, clear, and exact description, such as will enable others skilled in the art to which it 10 appertains to make and use the same.

This invention relates to apparatus for dispensing flexible articles one by one from a suitable support and with respect to its more specific features to apparatus for dispensing flexible resilient conical cups of 15 paper or like material from a column of closely nested cups.

One of the objects of the invention is the provision of a practical device of simple 20 and relatively inexpensive construction and such as to minimize tendency to dispense the cups in other than the predetermined manner.

Another object of the invention is the 25 provision of an efficient device of the character described which may take advantage of the character of the material and of the shape of the cups in effecting the dispensing thereof.

30 The invention accordingly comprises the features of construction, combinations of elements and arrangement of parts, which will be exemplified in the constructions hereinafter set forth and the scope of the 35 application of which will be indicated in the claims.

For a fuller understanding of the nature and objects of the invention reference should be had to the following detailed description taken in connection with the accompanying drawing, in which:

Figure 1 shows the apparatus largely in plan, a portion of the frame being broken away to disclose the underlying parts;

45 Figure 2 is a transverse sectional elevation of Fig. 1 taken through the drawing rolls, parts of the cup magazine being omitted;

Figure 3 is a sectional elevation taken at substantially right angles to Fig. 2;

50 Figure 4 is an elevation, partly in section, looking at the device from the side opposite that disclosed in Fig. 2, the dome being broken away;

Figure 5 is a detail of one of the drawing 55 rollers and a portion of its shaft; and

Figure 6 is a diagram illustrating a cup and certain relations thereof to the cup support.

Referring now more specifically to the drawing, the numeral 1 indicates the side, or 60 enclosing wall, of a casing which depends from a frame, or frame support 3, this plate being normally horizontally disposed and provided with an extension or bracket 2 for attachment to a wall bracket, a table or the like for supporting the dispenser in convenient position for use. The numeral 4 indicates a brace, being a ring fixed to the upper ends of and bracing the guide rods 5 standing from the plate 3. The numeral 6 70 indicates the cups which, as illustrated, are conical. In normal shape the open end, or mouth, of each cup lies in a single plane. The cups are made of paper, usually folded into conical shape, and are flexible and 75 resilient. A portion of a column of such cups appears in Fig. 4, the lowermost cup of the column being supported by a rigid member so as to depend through an opening 8 in the plate 3, into cooperative relation with the 80 cup gripping and drawing mechanism hereinafter described. The column of closely nested cups 6 may be inserted through the opening provided by the ring 4 so as to lie between the guide rods 5 and be guided by 85 the latter on their descent to the support as the cups are removed one by one from the bottom of the column. A cover, or dome 7, which may be of glass closed at the top, may be removably mounted upon the plate 3 to 90 enclose the column of cups and the rods 5.

The element which directly supports the column of cups in position for dispensing is indicated at 10, being a flat cup supporting ring or ring-like member, seated in a recess 95 9 in the plate 3 and providing an opening through which the lowermost cup projects and through which it may be drawn by the cup drawing mechanism. Portions of the inner edge of this ring serve as cup supporting shoulders to contact with the outer wall of the lowermost cup, and of the succeeding cups as they descend, so as to support the lowermost cup in position to be drawn and thereby dispensed. By making the ring 10 of 100 thin material its vertical dimension readily cooperates with even closely nested cups. Preferably, the inner edge of the ring 10 is disposed inwardly beyond the edge of the opening 8 so that the cups are wholly sup- 105 110

ported by the ring. The ring may be conveniently held in place by reduced extensions 11 of the rods 5, these extensions passing through the plate 3 and having their 5 threaded ends engaged by the nuts 12.

The cup gripping and drawing mechanism includes a gripping and drawing roll 13 operatively connected to rotate with the roll shaft 14. In the embodiment illustrated, a pair of drawing rolls similar in construction is employed. Each drawing roll comprises a metal body fastened to the shaft 14, said shaft being rotatably mounted in a bearing bracket 15 supported by the 10 plate 3. In the present embodiment a separate bracket 15 is employed for each drawing roll, and horizontally projecting from each bracket 15 is a bearing or sleeve 21 in which the shaft 14 is rotatably supported. 15 The drawing rolls 20 are disposed below the cup support 10 and lie on opposite sides of the lowermost cup of the cup column. In the present embodiment they are so related to each other and to the cup support 10 that 20 the lowermost cup in the column is closely adjacent the peripheries of the drawing rolls. The bearings 21 may extend from the bracket 15 to the side of the rolls and be of such a rigid character as to reliably support 25 the rolls in operative relations to the cups.

Means are provided to rotate the rolls while in contact with the cup so as to detach the cup from the support and from the other cups in the column. In the present embodiment, one of the shafts 14 is provided with a crank 17 which may have a suitable handle 22. Pinned to the shafts 14 are the gears 16, one mounted on one of the bearing brackets 15, and the other on the other bracket. 30 The numerals 18 and 19 indicate a pair of intermeshing gears, one of which meshes with the gear 16 of one of the shafts 14, and the other of which meshes with a similar gear 16 of the other shaft 14. The several 35 gears, 16, 18 and 19, form driving connections between the roll shafts and the driving member, or shaft 14.

The gripping and drawing rolls are provided with soft, frictional, peripheral faces 50 which come in contact with the cup effectively frictionally to grip the same and upon rotation to draw the cup from the cup support. In the present embodiment, said face is provided by a soft rubber band 20 encircling the body of each drawing roll and lying in a recess therein. This recess is curved axially of the roll so that the outer face of the band is generally accommodated to the peripheral shaft of the cup. In the 55 present embodiment as the drawing rolls rotate, their frictional face portions approach and recede from the longitudinal axis of the cup, and to this end the axes of the friction drawing rolls are eccentric to the cup contacting rubber faces 20. Thus said faces in-

clude cup contacting portions at unequal distances from the axes of rotation of the rolls respectively. The cup contacting faces furthermore are of sufficient peripheral extent not only to draw the cup from the support, 70 but to discharge the detached cup from the drawing mechanism, permitting the cup to drop through an opening 23 in the lower part of the casing 1, where it may be arrested by a lip 24 in conjunction with the wall of the opening 23. Sufficient peripheral extent for discharge is provided, when the rolls are of small diameter, by making the friction faces of the drawing rolls continuous around the rolls. 75

It is found in practice that the dispensing operation of the drawing rolls is facilitated by resiliently opposing receding movement of the roll in respect to the longitudinal axis of the cup path during the drawing operation. To effect this resilient opposition and to urge the rolls toward each other during drawing, one of the bearing brackets 15 is permitted an oscillatory movement, so that the shafts 14 may have a similar movement in respect to each other. The numeral 25 indicates a pivot pin having a screw connection with one of the brackets 15 and serving to support said bracket for oscillatory movement on the plate 3 transversely of the longitudinal axis of the cups, the drawing rolls 13 being thereby permitted to have relative approaching and receding movements transversely of the cups. As illustrated, said oscillatory movement is in a plane parallel to the supporting plane of the cup supporting ring 10. The numeral 26 indicates a flat spring, being an extension of a spring plate 27 bolted to the oscillatory bracket 15, the extension pressing against the face of the other bracket 15 and tending to urge the correspondingly supported drawing roll toward the other roll. In the embodiment illustrated, the bracket supporting the other roll is fixed in relation to the frame. Inasmuch as in the present embodiment the gear 18 is mounted on the fixed bracket and the gear 19 on the oscillatory bracket, the oscillatory movement of one bracket causes relative sidewise movement between the gears 18 and 19. However, these gears are prevented from operative disengagement by the provision of a slot 28 in the plate 3 in conjunction with a pin 29 upstanding from the oscillatory bracket into engagement with said slot. The pin and slot arrangement limits the amplitude of the oscillatory movement between the gears and between the friction drawing rolls. 105

Operation.—A column of the nested cups is placed in the cup magazine, the lowermost cup projecting through the opening in the cup support 10 and resting upon the cup supporting shoulders provided by the opening. The lowermost cup depends sufficiently to 110

enter between the cup drawing rolls. By turning the crank 17, the drawing rolls will be rotated and their friction faces will cooperate to grip the lowermost cup and draw the same from the ring 10. The next adjacent cup will be arrested by the ring. Due to the eccentric mounting of the drawing rolls, the lowermost cup will be squeezed and thereby collapsed in a predetermined transverse direction, as illustrated diagrammatically by the dotted lines in Fig. 6, so that the edges of its mouth adjacent the ends of the diameter at right angles to the line of squeezing will be flexed downwardly so as to be drawn past the inner edge of the cup supporting ring 10 at such points. Rotation of the drawing rolls will effect complete separation of the lowermost cup from the support and continued rotation will eventually discharge the drawn cup from between the rolls. As the rolls start to operate on the cups their lesser radii are presented toward the cups. Rotation thereafter causes the cups to be squeezed due to the increased radial lengths presented to the cups. After the lowermost cup has been detached, it may be collapsed further on account of the further increase in radial length referred to, but eventually the radial lengths presented to the cups will begin to decrease and the peripheral surfaces of the drawing rolls will therefore recede from each other better to accommodate the increasing diameter of the cup as it is drawn between the rolls.

The drawing rolls are disposed opposite each other diametrically of the cups and operate to squeeze the cups along the similarly located general diameter or line. As the column of cups rests in the ring 10 the cups are supported by the oppositely disposed shoulders, or edges, of the ring at points substantially in longitudinal alignment with the line of squeezing. When the cups are squeezed, they expand in a direction at right angles to the line of squeezing during actuation of the drawing mechanism, and the cup support is of such a character as to permit such expansion without injuring the cup. In the embodiment illustrated, the opening in the cup supporting ring 10 is oval, or elliptical in form, the minor axis of such oval being in substantially the same longitudinal plane as the line of squeezing referred to. Upon the flexing of the cups by the squeezing operation, as indicated diagrammatically in Fig. 6, it is desirable that the mouths of the cups adjacent the major axis of the oval remain out of contact with the ring after flexing. To this end, the inner edge of the ring adjacent to the major axis of the oval should preferably terminate in a plane 30 which is above the plane 31 to which the cup mouth is collapsed adjacent said major axis. In the present embodiment, therefore, as the column of cups lies in supported relation to the ring

10, the inner edges of said ring initially support the cups by a contact of the ring portions between the dotted lines A and B, the lowermost cup being out of contact with the ring adjacent the ends of the major axis of the latter. Upon the occurrence of the squeezing operation hereinbefore referred to, the lowermost cup is collapsed, as indicated in Fig. 6. This collapsing tends to free the lowermost cup from the ring, whereas the cup immediately there-above tends to be caught by the ring and restrained from passing therethrough.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. A dispensing apparatus of the character described including, in combination, a support for a column of nested cups, a pair of cup drawing friction rolls rotatable on axes extending transversely of the cup path and adapted to cooperate to grip and draw the end cup of said column from said support, a pair of roll shafts with which said rolls rotate, bearings for said shafts, one of said bearings being movable to effect relative approaching and receding movement between said rolls transversely of the cup, means including a spring for effecting relative movement between said bearings to cause approaching movement of said rolls, a driving member, and driving connections between said roll shafts and driving member.

2. A dispensing apparatus of the character described including, in combination, a support for a column of nested cups, a pair of cup drawing friction rolls rotatable on axes extending transversely of the cup path and adapted to cooperate to grip and draw the end cup of said column from said support, a pair of roll shafts with which said rolls rotate, bearings for said shafts, one oscillatable toward and from the other, a spring operative to urge said bearings toward each other, and roll driving means including a pair of intermeshing gears one of which is mounted on said oscillatable bearing.

3. A dispensing apparatus of the character described including, in combination, a frame, an oval cup supporting ring carried by said

frame, a pair of bearing brackets mounted on said frame, one of said brackets being oscillatable in a plane parallel to said ring, a pair of roll shafts mounted in said brackets below said ring, friction drawing rolls rotatable with said roll shafts adapted to cooperate with each other to squeeze an intermediate cup and collapse the cup in the direction of the minor axis of said ring, a spring tending to force one drawing roll in the direction of the other, and means adapted to rotate said roll shafts in unison.

4. A dispensing apparatus of the character described including, in combination, a frame, an oval cup supporting ring carried by said frame, a pair of bearing brackets mounted on said frame, one of said brackets being oscillatable in a plane parallel to said ring, a pair of roll shafts mounted in said brackets below said ring, friction drawing rolls rotatable with said roll shafts adapted to cooperate with each other to squeeze an intermediate cup and collapse the cup in the direction of the minor axis of said ring, a spring tending to move one shaft in the direction of the other, and means adapted to rotate said roll shafts in unison including gears on said shafts and intermediate gears meshing with each other, one of said intermediate gears being oscillatable with said oscillatory bracket.

5. A dispensing apparatus of the character described including, in combination, a frame, an oval cup supporting ring carried by said frame, a pair of bearing brackets mounted on said frame, one of said brackets being oscillatable in a plane parallel to said ring, a pair of roll shafts mounted in said brackets below said ring, friction drawing rolls rotatable with said roll shafts having peripheral drawing faces of soft, frictional material, eccentric to the axes of said shafts, respectively, adapted to cooperate with each other to squeeze an intermediate cup and collapse the cup in the direction of the minor axis of said ring, a spring tending to move one shaft in the direction of the other, and means adapted to rotate said roll shafts in unison including gears on said shafts and intermediate gears meshing with each other, one of said intermediate gears being oscillatable with said oscillatory bracket.

5. A dispensing apparatus of the character described including, in combination, a frame, an oval cup supporting ring carried by said frame, a pair of bearing brackets mounted on said frame, one of said brackets being oscillatable in a plane parallel to said ring, a pair of roll shafts mounted in said brackets below said ring, friction drawing rolls rotatable with said roll shafts having peripheral drawing faces of soft, frictional material, eccentric to the axes of said shafts, respectively, adapted to cooperate with each other to squeeze an intermediate cup and collapse the cup in the direction of the minor axis of said ring, a spring tending to move one shaft in the direction of the other, and means adapted to rotate said roll shafts in unison including gears on said shafts and intermediate gears meshing with each other, one of said intermediate gears being oscillatable with said oscillatory bracket.

In testimony whereof I affix my signature.
HAROLD CARLE.
